W. A. BARRY,
TAMBOURINE,
APPLICATION FILED AUG. 23, 1921.

1,434,278.

Patented Oct. 31, 1922.

UNITED STATES PATENT OFFICE.

WILLIAM A. BARRY, OF PHILADELPHIA, PENNSYLVANIA, ASSIGNOR TO BARRY DRUM MANUFACTURING COMPANY, OF PHILADELPHIA, PENNSYLVANIA.

TAMBOURINE.

Application filed August 23, 1921. Serial No. 494,555.

To all whom it may concern:

Be it known that I, WILLIAM A. BARRY, a citizen of the United States, residing at Philadelphia, in the county of Philadelphia and State of Pennsylvania, have invented new and useful Improvements in Tambourines, of which the following is a specification.

This invention relates to a tambourine, and the object is to provide improved means for securing the head in position, and additional means, also of improved construction, for mounting the jingles.

The device comprises an annular element 15 constituting a frame formed with openings at intervals and with a bead on one outer edge, a clamping ring for retaining the skin upon the head in engagement with the bead, and means for mounting the jingles with 20 the aforesaid opening, the mounting devices serving also to connect an additional annular element with that first named.

The invention consists further in the novel construction, combination and arrangement 25 of elements hereinafter described and claimed, it being understood that modifications may be made within the scope of the claims, without departing from the spirit of the invention.

30 In the accompanying drawings:

Figure 1 is a plan view of the instrument.

Figure 2 is a fragmentary view, partly in elevation and partly in section, showing the manner of securing the head by means 35 of an annular band, and showing the mounting of the jingles.

Figure 3 is a fragmentary view transversely through the frame and transversely of the plate constituting the jingles.

40 Figure 4 is a fragmentary view in elevation showing the manner of connecting the ends of the clamping rings.

In carrying out the invention I provide a frame of annular form and designated 10, this annular element having cut-away portions providing openings 11 in which the jingles are mounted. In view of the formation of the openings at spaced intervals, the supports or posts 12 are provided and 50 each being formed with a concaved upper end portion or outer end portion.

The head 14 is clamped on the frame 10 and engages the bead 15, the clamping ring

16 serving to retain the edge portion of the head in contact with the bead, so that positive engagement may be retained. 55

Within each of the openings I mount a pair of plates, or jingling elements, these plates being designated 18 and 19, that is the two plates of any given pair are so 60 designated. The plates are apertured centrally and threaded pins or screws 21 pass through the apertures in the manner shown in Figure 3, and enter the solid portion of the frame 10. 65

An annular element 24 of suitable cross section is provided with apertures at spaced intervals, and the screws pass through these apertures and then through the plates and into the frame 10. The heads of the screws 70 are countersunk as shown and the element 24 rests within the concaved portions of posts or supports 12.

The clamping ring is provided with offset elements 26 and 27 on the ends thereof, 75 these elements being apertured, and a screw 29 passes through the apertures and is engaged and retained by a nut 30, so that the required tension may be placed upon the band, for securing the head in position. 80

By securing the ring or annular element 24 in the manner specified, I arrange for mounting the plates or jingles without the use of additional or separate mounting means and therefore not only reduce to a 85 certain extent the cost of the manufacture, but there are fewer elements likely to work loose during the use of the device.

What is claimed is:

1. An instrument of the class described comprising an annular element having cut-away portions opening toward one edge thereof providing intermediate solid supports formed with the body of the annular element, a second annular element of the 95 same diameter as that first named and contacting with the ends of the supports, devices passing through the second named annular element and into that first named, and loosely mounted plates retained in position in the openings by said devices, and a head on the first named annular element. 100

2. An instrument of the class described comprising an annular element and projecting devices thereon arranged to provide 105 spaced openings and intermediate solid por-

tions having concave ends, a second annular element of the same diameter as that first named and approximately circular in cross section, the second annular element contact-
5 ing with the concave ends, a head mounted on the annular element first named, screws passing through the second named annular

element and entering that first named, the screws passing through the open portions and loosely mounted plates carried by the 10 screws and serving as jingles.

In testimony whereof I affix my signature.

WILLIAM A. BARRY.
